JOSEPH W. HALLER, OF HARRISON, NEW JERSEY.

COMBINATION-FAUCET OR MIXING-VALVE.

1,068,125.

Specification of Letters Patent.

Patented July 22, 1913.

Application filed October 19, 1912. Serial No. 726,624.

To all whom it may concern:

Be it known that I, JOSEPH W. HALLER, a citizen of the United States, residing at Harrison, in the county of Hudson and State of New Jersey, have invented certain new and useful Improvements in Combination-Faucets or Mixing-Valves; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference, generally, to improvements in that class of valves, known as combination faucets; and, the invention relates, more particularly, to a novel form of combination faucet comprising a suitable casing and a spindle, adapted to be turned in either a forward direction from right to left, or in a rearward direction from right to left, for the purpose of operating singly or separately a plurality of valves having hot and cold water-connections, and by means of the same spindle simultaneously operating both valves, all with a view of providing a combination faucet having a single operating handle by means of which either of the valves may be operated singly, or both valves may be operated simultaneously, for delivery, at will, of either hot or cold water, or a graduated mixture of hot and cold water, according to the desires of the operator.

The invention has for its further object to provide a combination valve or faucet of the general character hereinafter more particularly set forth, which shall be of a most simple and efficient construction, and in which the arrangement of the parts is such that the valve-disks and washers can be readily renewed in case of wear.

Other objects of the present invention not at this time more particularly enumerated will be clearly understood from the following detailed description of the present invention.

With the various objects of the present invention in view, the said invention consists, primarily, in the novel combination faucet or mixing valve hereinafter set forth; and, the invention consists, furthermore, in the novel arrangements and com-

bination of the various devices and parts, as well as in the details of the construction of the same, all of which will be more fully described in the following specification and then finally embodied in the clauses of the claim which are appended and which form an essential part of the said specification.

The invention is clearly illustrated in the accompanying drawings, in which:

Figure 1 is a view partly in front elevation and partly in longitudinal vertical section of a combination faucet or valve, showing one embodiment of the principles of the present invention; and Fig. 2 is a top view of the same, with a horizontal sectional representation of the central portion of the valve-casing and of the cam-shaped portion of the operating handle or spindle of the combination faucet. Fig. 3 is an end view of the combination faucet or valve; and Fig. 4 is a transverse vertical section of the valve-casing and one of the valve-stems, said section being taken on line 4-4 in said Fig. 1, looking in the direction of the arrow x. Fig. 5 is a part front elevation and a part longitudinal vertical section of a combination faucet or valve of a slightly modified construction, but still embodying the principles of the present invention; and Fig. 6 is a horizontal sectional representation of the same, said section being taken on line 6-6 in said Fig. 5, looking in the direction of the arrow y. Fig. 7 is a top view of the cover and operating handle employed with the construction represented in said Figs. 5 and 6, removed from the valve-casing; and Fig. 8 is a detail horizontal sectional representation of the cam-shaped portion of the valve-operating spindle.

Similar characters of reference are employed in all of the said above described figures, to indicate corresponding parts.

Referring now to the said drawings, the reference-character 1 indicates a suitable shell or casing, preferably cylindrical in form and horizontally positioned with its respective and screw-threaded end-members 2, which are preferably internally screw-threaded and are closed by means of removably disposed screw-plugs, as 3. Extending laterally and rearwardly from the sides of the end-members 2 of the said shell or casing 1 are suitably formed inlet-ports, as 4 and 5, respectively, for the attachment of

the said shell or casing 1, in any suitable manner, to the hot and cold water pipes, respectively, as will be clearly evident. Extending upwardly from the central or middle part of the said shell or casing 1 is a tubular member, as 6 which is externally screw-threaded, as at 7, for the reception thereon of a perforated and spindle-receiving nut 8, as clearly illustrated in Figs. 1 and 3 of the drawings. The said tubular member 6 forms, with the inner chambered central portion of the shell or casing 1, a spindle-receiving chamber 9, said chamber 9 being separated from the valve-receiving chambers 10 in the respective end-portions or members 2 of the shell or casing 1 by an arrangement of two partitions, 11, each partition being provided with a valve-stem receiving bearing-portion 12, and an opening, as 13, said openings establishing communication between the chambers 10 and the spindle-receiving chamber 9.

Projecting in a downward direction from the central portion of the shell or casing 1, and in communication with the chamber 9, is a tubular outlet port or nozzle 14. Within the said spindle-receiving chamber 9 and extending through the perforation in the previously-mentioned nut 8 is a spindle 15 provided upon its upper free end-portion with a suitably formed operating handle, as 16. Within the said chamber 9 is an annular shoulder, as 17, which forms an annular seat upon which rests and is rotatably arranged an enlarged seating member or element, as 18, with which the said spindle 15 is provided, said seating member or element 18 being preferably formed with the tapering surface-portion 19, upon which is arranged a suitable packing-fabric 20. Mounted upon the spindle 15, above the said packing-fabric 20, is a suitable metallic packing ring 21, the parts all being arranged so that a water-tight joint will be the result, when the nut 8 is screwed down tightly upon the screw-threaded portion of the tubular member 6 and against the said packing ring 21, as will be clearly evident. Upon the spindle, beneath the said seating member or element 18, is a valve-stem actuating element 22, made in the form of a cam-member of the general configuration shown more particularly in Figs. 2 and 8 of the drawings, the said cam-member having the larger arc-shaped and convex surface-portion 23, contiguous and adjacent to which are two smaller arc-shaped and convex surface-portions 24 and 25. Extending from the concave surface-positions 26 and 27 contiguous and adjacent to the respective convex surface-positions 24 and 25, are a pair of laterally projecting and straight or flat surface-positions 28 and 29, connected by an arc-shaped and convex connecting surface 30. I have particularly in the above set forth the

peculiar surface-conformations of the said valve-stem actuating element or cam-member 22, because it is owing to this particular arrangement of the various portions of the said element or member 22 that the valve-stems and their valve-disks may be operated singly or independently of each other, or one valve-disk may be fully unseated and the other valve may be regulably unseated while the first mentioned valve-disk is fully unseated, so as to produce any desired mixtures of hot and cold water, or other liquids.

Slidably arranged in the previously-mentioned bearing or guiding portions 12 with which the partitions 11 are provided, are valve-stems 31, each valve-stem having a suitable point end-portion, as 32, extending into the chamber 9 and adapted to be engaged by the said valve-stem actuating element or cam-member 22, as will hereinafter more fully appear. The opposite end-portions of the said valve-stems 31 project into the respective valve-chambers 10, being provided with suitably formed valve-disks 33, adapted to be normally seated upon suitable valve-seats, as 34, by the action of suitable coil-springs 35 which are arranged between said valve-disks and the closing plugs 3 in the respective open ends of the end-members 2 of the shell or casing, and are always under compression between the said valve-disks and the said plugs.

Referring now to Figs. 5, 6, and 7 of the drawings, it will be seen, that the main central portion of the shell or body 1 is formed with a slightly upwardly projecting part 37, formed with an annular off-set 38, for the reception of a suitable cap, as 39, which is detachably secured upon the said upwardly projecting part 37 preferably by means of screws 40, substantially in the manner illustrated in said Fig. 5 of the drawings. In this modified construction the spindle 15 is made upon its upper end with a reduced portion, as 41, a portion of which is rotatably mounted in a hole 42 with which the cap 39 is provided, said hole 42 forming a suitable bearing-portion for the said spindle, as will be clearly evident. The spindle in all other respects is the same as the spindle shown and described in connection with Figs. 1, 2 and 3 of the drawings. However, to maintain the packing-fabric in its properly mounted position upon the said spindle 15, a sleeve or nut-like member 43 is mounted upon said spindle, said sleeve or nut-like member being externally screw-threaded, as at 44, and being screwed into an internally screw-threaded receiving portion 45, as clearly shown and for the purposes, which will be evident from an inspection of said Fig. 5 of the drawings. Suitably mounted upon the reduced portion 41 of the spindle 15 is a gear-wheel 36, and in mesh with said gear-wheel 36 is a pinion 46 suitably mount-

ed upon an operating stem or spindle 47 which is provided upon its free end-portion with a handle 48. This stem or spindle 47 is rotatably arranged in a bearing-portion 49 in the cap 39 and in a bearing-socket 50 with which the previously-mentioned upwardly projecting part 37 of the main shell or casing is provided. If desired, the said spindle 47 may be provided upon its portion 5 outside of the cap 39 with an index hand or pointer, as 51, which is moved with the handle 48 and the stem or spindle 47 in either direction against suitable stops 52 and 53 with which the cap 39 is provided, the said stops being preferably indicated by the words "Hot" and "Cold," so that the operator can readily turn the handle in the right direction to obtain either hot or cold water; or a proper mixture of the same. A coiled spring 54 may also be used, said spring encircling a portion of the spindle or operating stem 47, having one end-portion secured to said stem 47 and the other end-portion to said projecting part 37, the purpose of the said spring being for returning the operated stem 47 and its handle, as well as the spindle 15 and its parts, to their normal initial positions. The arrangement of the valve-disks and their stems, as well as the arrangement and construction of the cam-member for actuating said valve-stems and valve-disks, is the same as herein-before described in connection with Figs. 1, 2, 3, 4, and 8 of the drawings, and need not, therefore, be again described in detail.

Having in the foregoing set forth the general construction of a combination faucet or mixing valve made according to and embodying the principles of the present invention, I will now briefly set forth its manner of operation for drawing a supply of either hot or cold water, or for drawing any desired mixture of hot and cold water.

Referring now to Fig. 1 of the drawings, it will be evident that when the handle or lever 16 of the spindle 15 is moved in a forward direction, from right to left, looking toward the main shell or casing 1, the cam-surface 24 is immediately brought into sliding engagement with the pointed end-portion 32 of the right-hand valve-stem 31, whereby the valve-disk 33 is moved off its valve-seat 34, so that a supply of water, say the cold water, is free to pass from the chamber 10, at the right-hand end of the shell or casing 1, through the passage-way 13, into the chamber 9 and out of the nozzle or outlet 14. The distance that the valve-disk 33 is moved away from its seat 34, to regulate the quantity of the flow of the cold water into the chamber 9 and from the nozzle 14, is controlled by the convexity of the moving cam-surface 24, so that when the cam-surface 23 has been moved into engagement with the end-portion 32 of the right-

hand valve-stem, the valve-disk has been moved to its full extent and the maximum supply of cold water flows through the opened valve. This happens with about one-eighth of a turn of the handle 16 and 5 spindle 15. When it is desired to temper the cold water, a regulatable quantity of hot water may be added, by continuing the direction of the movement of the handle from right to left, the right hand valve-stem and valve disk being still maintained in their open relations, but the flat surface 29 is gradually brought into its active engagement with the pointed end-portion 32 of the left-hand valve-stem 31, which is operated so as to move the left-hand valve-disk from its seat to admit a regulated quantity of hot water into the chamber 9, where it mixes with the cold water, and thereby suitably tempers the water, as will 10 be evident. By still continuing the movement of the handle 16 from right to left, the cam-surface 30 is brought into engagement with the end-portion of the left-hand valve stem, whereby the left-hand valve-disk is moved from its seat to its fullest extent, and a combined maximum supply of cold and hot water will flow into the chamber 9, which passes out therefrom through the nozzle 14. When the handle 16 is returned to its normal initial position, the springs 35, as will be evident, coöperate with the unseated valve-disks to return them to their seated and closed positions, to thereby shut off the flow of the water. In moving the handle from its normal initial position, in a rearward direction from right to left, the left-hand valve-stem and valve-disk can be operated without unseating the right-hand valve-disk, so that a maximum 15 supply of hot water may be obtained. Similarly, this supply of hot water can be tempered by continuing the said movement of the handle 16, whereby the flat surface 28 and the cam-surface 30 can be brought 20 into engagement with the pointed end-portion of the right-hand valve-stem, so as to unseat the right-hand valve-disk to admit a regulated supply of cold water which reduces the temperature of the flowing hot 25 water. With the construction represented in Fig. 5 of the drawings, the same results can be made to take place, except that owing to the geared arrangement of the spindles, differential rotary movements of said 30 spindles take place, so that the valve-disks are more quickly unseated, with the same movement of the handle 48, the spring 54 returning the parts to their normal initial 35 positions, as soon as the operator removes his or her hand from the handle 48, as will be clearly understood from an inspection of said Fig. 5.

While my present invention is especially adapted for use as a hot and cold water 40

combination faucet, it will be evident that the device may be used as a mixing valve, for regulatably mixing different kinds of liquid.

I am aware that changes may be made in the general arrangements and combinations of the various devices and parts, as well as in the details of the construction of the same, without departing from the scope of the present invention as set forth in the foregoing specification, and as defined in the clauses of the claim which are appended thereto. Hence, I do not limit my present invention to the exact arrangements and combinations of the various devices and parts as described in the foregoing specification, nor do I confine myself to the exact details of the construction of the said parts as illustrated in the accompanying drawings.

I claim:

1. A combination faucet or mixing valve comprising a main shell or casing formed with a spindle-receiving chamber, and a pair of end-members forming valve-receiving chambers, each end-member being provided with an inlet-port, and the spindle-receiving chamber being provided with an outlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem-receiving guide in each partition, a valve-disk normally seated upon each valve-seat, a valve-stem extending from each valve-disk, each valve-stem being slidably mounted in the guide and each valve-stem having a portion extending into the said spindle-receiving chamber, a rotary spindle in said spindle-receiving chamber, and means connected with said spindle adapted to be brought into engagement with either or both of the end-portions of said valve-stems, for singly unseating either valve or disk, or for fully unseating one of said valve-disks and regulably unseating the other valve-disk while said first-mentioned valve-disk is fully unseated, substantially as and for the purposes set forth.

2. A combination faucet or mixing valve comprising a main shell or casing formed with a spindle-receiving chamber, and a pair of end-members forming valve-receiving chambers, each end-member being provided with an inlet-port, and the spindle-receiving chamber being provided with an outlet port, partitions dividing said valve-receiving chambers from said spindle-receiving chamber, each partition having an opening providing a means of communication between the adjacent valve-receiving

chamber and the spindle-receiving chamber, a valve-seat in each valve-receiving chamber, and a valve-stem-receiving guide in each partition, a valve-disk normally seated upon each valve-seat, a valve-stem extending from each valve-disk, each valve-stem being slidably mounted in the guide and each valve-stem having a portion extending into the said spindle-receiving chamber, a rotary spindle in said spindle-receiving chamber, and a cam-shaped element connected with said spindle adapted to be brought into sliding engagement with either or both of the end-portions of said valve-stems, for singly unseating either valve-disk, or for fully unseating one of said valve-disks and regulably unseating the other valve-disk while said first-mentioned valve-disk is fully unseated, substantially as and for the purposes set forth.

3. A combination faucet or mixing valve comprising a main shell or casing formed with a spindle-receiving chamber, and a pair of end-members forming valve-receiving chambers, each end-member being provided with an inlet-port, and the spindle-receiving chamber being provided with an outlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a valve-stem extending from each valve-disk, each valve-stem being slidably mounted in the guide and each valve-stem having a portion extending into the said spindle-receiving chamber, a rotary spindle in said spindle-receiving chamber, and a cam-shaped element connected with said spindle, comprising a convex cam-surface 23, a pair of adjacent and smaller convex cam-surface 24 and 25, a pair of flat surfaces 28 and 29, and a connecting convex cam-surface 30, arranged and adapted to be brought into sliding engagement with either or both of the end-portions of said valve-stems, for singly unseating either valve-disk, or for fully unseating one of said valve-disks and regulably unseating the other valve-disk while said first-mentioned valve-disk is fully unseated, substantially as and for the purposes set forth.

4. A combination faucet or mixing valve comprising a main shell or casing formed with a spindle-receiving chamber, and a pair of open-ended end-members forming valve-receiving chambers, each end-member having a detachable closing means in its open end, and each end-member being provided with an inlet-port, partitions di-

- viding said valve-receiving chambers from said spindle-receiving chamber, each partition having an opening providing a means of communication between the adjacent 5 valve-receiving chamber and the spindle-receiving chamber, a valve-seat in each valve-receiving chamber, and a valve-stem receiving guide in each partition, a valve-disk normally seated upon each valve-seat, a coiled spring within each valve-receiving chamber located between the valve-disk and the detachable closing means, a valve-stem extending from each valve-disk, each valve-stem being slidably mounted in the guide 10 and each valve-stem having a portion extending into the said spindle-receiving chamber, and means connected with said spindle adapted to be brought into engagement with either or both of the end- 15 portions of said valve-stems for singly unseating either valve-disk, or for fully unseating one of said valve-disks and regulably unseating the other valve-disk while said first-mentioned valve-disk is fully unseated, substantially 20 as and for the purposes set forth. 25
5. A combination faucet or mixing valve comprising a main shell or casing formed with a spindle-receiving chamber, and a pair of open-ended end-members forming valve-receiving chambers, each end-member having a detachable closing means in its open end, and each end-member being provided with an inlet-port, partitions dividing said valve-receiving chambers from said spindle-receiving chamber, each partition having an 30 opening providing a means of communication between the adjacent valve-receiving chamber and the spindle-receiving chamber, a valve-seat in each valve-receiving chamber, each partition having an 35 opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a coiled spring within each valve-receiving chamber located between the valve-disk and the detachable closing means, 40 a valve-stem extending from each valve-disk, each valve-stem being slidably mounted in the guide and each valve-stem having a portion extending into the said spindle-receiving chamber, and a cam-shaped element 45 connected with said spindle adapted to be brought into sliding engagement with either or both of the end-portions of said valve-stems, for singly unseating either valve-disk, or for fully unseating one of said valve-disks and regulably unseating the other valve-disk while said first-mentioned valve-disk is fully unseated, substantially as and for the purposes set forth. 50
6. A combination faucet or mixing valve comprising a main shell or casing formed with a spindle-receiving chamber, and a pair of open-ended end-members forming valve-receiving chambers, each end-member having a detachable closing means in its open 55 end, and each end-member being provided with an inlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a valve-stem extending from each valve-disk, each valve-stem being slidably mounted in the guide and each valve-stem having a portion extending into the said spindle-receiving chamber, a rotary valve-stem operating spindle in said spindle-receiving chamber, and means connected with said spindle adapted to be brought into engagement with either or both of the end-portions of said valve-stems, for singly unseating either valve or disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle rotatably mounted with relation to said 60
- with an inlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a coiled spring within each valve-receiving chamber located between the valve-disk and the detachable closing means, a valve-stem extending from each valve-disk, each valve-stem being slidably mounted in the guide and each valve-stem having a portion extending into the said spindle-receiving chamber, and a cam-shaped element connected with said spindle comprising a convex cam-surface 23, a pair of adjacent and smaller convex cam-surfaces 24 and 25, a pair of flat surfaces 28 and 29, and a connecting convex cam-surface 30, arranged and adapted to be brought into sliding engagement with either or both of the end-portions of said valve-stems, for singly unseating either valve-disk, or for fully unseating one of said valve-disks and regulably unseating the other valve-disk while said first-mentioned valve-disk is fully unseated, substantially as and for the purposes set forth. 65
7. A combination faucet or mixing valve comprising a main shell or casing formed with a spindle-receiving chamber, and a pair of end-members forming valve-receiving chambers, each end-member being provided with an inlet-port, and the spindle-receiving chamber being provided with an outlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a valve-stem extending from each valve-disk, each valve-stem being slidably mounted in the guide and each valve-stem having a portion extending into the said spindle-receiving chamber, a rotary valve-stem operating spindle in said spindle-receiving chamber, and means connected with said spindle adapted to be brought into engagement with either or both of the end-portions of said valve-stems, for singly unseating either valve or disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle rotatably mounted with relation to said 70

main shell or casing, a pinion on said last-mentioned spindle in mesh with said gear-wheel, and a handle connected with said last-mentioned spindle, substantially as and for the purposes set forth.

8. A combination faucet or mixing valve comprising a main shell or casing formed with a spindle-receiving chamber, and a pair of end-members forming valve-receiving chambers, each end-member being provided with an inlet-port, and the spindle-receiving chamber being provided with an outlet port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a valve-stem extending from each valve-disk, each valve-stem being slidably mounted in the guide and each valve-stem having a portion extending into the said spindle-receiving chamber, a rotary valve-stem operating spindle in said spindle-receiving chamber, and a cam-shaped element connected with said spindle adapted to be brought into sliding engagement with either or both of the end-portions of said valve-stems, for singly unseating either valve-disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle-rotatably mounted with relation to said main shell or casing, a pinion on said last-mentioned spindle in mesh with said gear-wheel, and a handle connected with said last-mentioned spindle, substantially as and for the purposes set forth.
9. A combination faucet or mixing valve comprising a main shell or casing formed with a spindle-receiving chamber, and a pair of end-members forming valve-receiving chambers, each end-member being provided with an inlet-port, and the spindle-receiving chamber being provided with an outlet port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a coiled spring within each valve-receiving chamber located between the valve-disk and the detachable closing means, a valve-stem extending from each valve-disk, each valve-stem being slidably mounted in the guide and each valve-stem having a portion extending into the said spindle-receiving chamber, a rotary valve-stem operating spindle in said spindle-receiving chamber, and means connected with said spindle adapted to be brought into engagement with either or both of the end-portions of said valve-stems for singly unseating either valve-disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle-rotatably mounted with relation to said main shell or casing, a pinion on said last-mentioned spindle in mesh with said gear-wheel, and a handle connected with said last-mentioned spindle, substantially as and for the purposes set forth.
10. A combination faucet or mixing valve comprising a main shell or casing formed with a spindle-receiving chamber, and a pair of open-ended end-members forming valve-receiving chambers, each end-member having a detachable closing means in its open end, and each end-member being provided with an inlet-port, partitions dividing said valve-receiving chambers from said spindle-receiving chamber, each partition having an opening providing a means of communication between the adjacent valve-receiving chamber and the spindle-receiving chamber, and a valve-stem receiving guide in each partition, a valve-disk normally seated upon each valve-seat, a coiled spring within each valve-receiving chamber located between the valve-disk and the detachable closing means, a valve-stem extending from each valve-disk, each valve-stem being slidably mounted in the guide and each valve-stem having a portion extending into the said spindle-receiving chamber, a rotary valve-stem operating spindle in said spindle-receiving chamber, and means connected with said spindle adapted to be brought into engagement with either or both of the end-portions of said valve-stems for singly unseating either valve-disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle-rotatably mounted with relation to said main shell or casing, a pinion on said last-mentioned spindle in mesh with said gear-wheel, and a handle connected with said last-mentioned spindle, substantially as and for the purposes set forth.
11. A combination faucet or mixing valve

stem operating spindle in said spindle-receiving chamber, and a cam-shaped element connected with said spindle, comprising a convex cam-surface 23, a pair of adjacent and smaller convex cam-surface 24 and 25, a pair of flat surfaces 28 and 29, and a connecting convex cam-surface 30, arranged and adapted to be brought into sliding engagement with either or both of the end-portions of said valve-stems, for singly unseating either valve disk, or for fully unseating one of said valve-disks and regulably unseating the other valve disk while said first-mentioned valve-disk is fully unseated, and means for rotating said valve-stem operating spindle consisting of a gear-wheel mounted upon said spindle, a second spindle-rotatably mounted with relation to said main shell or casing, a pinion on said last-mentioned spindle in mesh with said gear-wheel, and a handle connected with said last-mentioned spindle, substantially as and for the purposes set forth.

12. A combination faucet or mixing valve comprising a main shell or casing formed with a spindle-receiving chamber, and a pair of open-ended end-members forming valve-receiving chambers, each end-member having a detachable closing means in its open end, and each end-member being provided with an inlet-port, partitions dividing said valve-receiving chambers from said spindle-receiving chamber, each partition having an opening providing a means of communication between the adjacent valve-receiving chamber and the spindle-receiving chamber, and a valve-stem receiving guide in each partition, a valve-disk normally seated upon each valve-seat, a coiled spring within each valve-receiving chamber located between the valve-disk and the detachable closing means, a valve-stem extending from each valve-disk, each valve-stem being slidably mounted in the guide and each valve-stem having a portion extending into the said spindle-receiving chamber, a rotary valve-stem operating spindle in said spindle-receiving chamber, and means connected with said spindle adapted to be brought into engagement with either or both of the end-portions of said valve-stems for singly unseating either valve-disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle-rotatably mounted with relation to said main shell or casing, a pinion on said last-mentioned spindle in mesh with said gear-wheel, and a handle connected with said last-mentioned spindle, substantially as and for the purposes set forth.

13. A combination faucet or mixing valve

comprising a main shell or casing formed with a spindle-receiving chamber, and a pair of open-ended end-members forming valve-receiving chambers, each end-member having a detachably closing means in its open end, and each end-member being provided with an inlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a coiled spring within each valve-receiving chamber located between the valve-disk and the detachable closing means, a valve-stem extending from each valve-disk, each valve-stem being slidably mounted in the guide and each valve-stem having a portion extending into the said spindle-receiving chamber, a rotary valve-stem operating spindle in said spindle receiving chamber, and a cam-shaped element connected with said spindle adapted to be brought into sliding engagement with either or both of the end-portions of said valve-stems, for singly unseating either valve-disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle rotatably mounted with relation to said main shell or casing, a pinion on said last-mentioned spindle in mesh with said gear-wheel, and a handle connected with said last-mentioned spindle, substantially as and for the purposes set forth. 12. A combination faucet or mixing valve comprising a main shell or casing formed with a spindle-receiving chamber, and a pair of end-members forming valve-receiving chambers, each end-member being provided with an inlet-port, and the spindle-receiving chamber being provided with an annular seat and an outlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a valve-stem extending from each valve-disk, each valve-stem being slidably mounted in the guide and each valve-stem having a portion extending into the said spindle-receiving chamber, a stuffing box connected with said spindle-receiving chamber for closing the same, a rotary spindle in said spindle-receiving chamber extending through said stuffing box and provided with an operating handle, an enlarged seating member connected with said spindle and rotatably seated upon the annular seat in said spindle-receiving chamber, and means connected with said spindle at a point beneath said seating member adapted to be brought into engagement with either or both of the end-portions of said valve-stems, for singly unseating either valve-disk, or for fully unseating one of said valve-disks and regulably unseating the other valve disk while said first-mentioned valve-disk is fully unseated, substantially as and for the purposes set forth. 14. A combination faucet or mixing valve comprising a main shell or casing formed with a spindle-receiving chamber, and a pair of end-members forming valve-receiving chambers, each end-member having a detachably closing means in its open end, and each end-member being provided with an inlet-port, partitions dividing said valve-receiving chambers from said spindle-receiving chamber, each partition having an opening providing a means of communication between the adjacent valve-receiving chamber and the spindle-receiving chamber, a valve-seat in each valve-receiving chamber, and a valve-stem receiving guide in each partition, a valve-disk normally seated upon each valve-seat, a coiled spring within each valve-receiving chamber located between the valve-disk and the detachable closing means, a valve-stem extending from each valve-disk, each valve-stem being slidably mounted in the guide and each valve-stem having a portion extending into the said spindle-receiving chamber, a rotary valve-stem operating spindle in said spindle receiving chamber, and a cam-shaped element connected with said spindle comprising a convex cam-surface 23, a pair of adjacent and smaller convex cam-surfaces 24 and 25, a pair of flat surfaces 28 and 29, and a connecting convex cam-surface 30, arranged and adapted to be brought into sliding engagement with either or both of the end-portions of said valve-stems, for singly unseating either valve-disk, or for fully unseating one of said valve-disks and regulably unseating the other valve-disk while said first-mentioned valve-disk is fully unseated, and means for rotating said valve-stem operating spindle consisting of a gear-wheel mounted upon said spindle, a second spindle rotatably mounted with relation to said main shell or casing, a pinion on said last-mentioned spindle in mesh with said gear-wheel, and a handle connected with said last-mentioned spindle, substantially as and for the purposes set forth.

chambers, each end-member being provided with an inlet-port, and the spindle-receiving chamber being provided with an annular seat and an outlet-port, partitions dividing 5 said valve-receiving chambers from said spindle-receiving chamber, each partition having an opening providing a means of communication between the adjacent valve-receiving chamber and the spindle-receiving 10 chamber, a valve-seat in each valve-receiving chamber, and a valve-stem receiving guide in each partition, a valve-disk normally seated upon each valve-seat, a valve-stem extending from each valve-disk, each 15 valve-stem being slidably mounted in the guide and each valve-stem having a portion extending into the said spindle-receiving chamber, a stuffing box connected with said spindle-receiving chamber for closing the 20 same, a rotary spindle in said spindle-receiving chamber extending through said stuffing box and provided with an operating handle, an enlarged seating member connected with said spindle and rotatably seated 25 upon the annular seat in said spindle-receiving chamber, and a cam-shaped element connected with said spindle at a point beneath said seating member adapted to be brought into engagement with either or both 30 of the end-portions of said valve-stems, for singly unseating either valve-disk, or for fully unseating one of said valve-disks and regulably unseating the other valve-disk while said first-mentioned valve-disk is fully 35 unseated, substantially as and for the purposes set forth.

15. A combination faucet or mixing valve comprising a main shell or casing formed with a spindle-receiving chamber, and a pair 40 of end-members forming valve-receiving chambers, each end-member being provided with an inlet-port, and the spindle-receiving chamber being provided with an annular seat and an outlet-port, partitions dividing

said valve-receiving chambers from said 45 spindle-receiving chamber, each partition having an opening providing a means of communication between the adjacent valve-receiving chamber and the spindle-receiving chamber, a valve-seat in each valve-receiving 50 chamber, and a valve-stem receiving guide in each partition, a valve-disk normally seated upon each valve-seat, a valve-stem extending from each valve-disk, each 55 valve-stem being slidably mounted in the guide and each valve-stem having a portion extending into the said spindle-receiving chamber, a stuffing box connected with said spindle-receiving chamber for closing the same, a rotary spindle in said spindle-receiving 60 chamber extending through said stuffing box and provided with an operating handle, an enlarged seating member connected with said spindle and rotatably seated upon the annular seat in said spindle-receiving chamber, and a cam-shaped element 65 connected with said spindle at a point beneath said seating member, comprising a convex cam-surface 23, a pair of adjacent and smaller convex cam-surfaces 24 and 25, 70 a pair of flat surfaces 28 and 29, and a connecting convex cam-surface 30, arranged and adapted to be brought into sliding engagement with either or both of the end-portions of said valve-stems, for singly unseating 75 either valve-disk, or for fully unseating one of said valve disks and regulably unseating the other valve-disk while said first-mentioned valve-disk is fully unseated, substantially as and for the purposes set forth. 80

In testimony, that I claim the invention set forth above I have hereunto set my hand this 16th day of October, 1912.

JOSEPH W. HALLER.
